COLLAPSIBLE WHIPSTOCK

John E. Brantly, Pasadena, Calif., assignor to
 Drilling and Exploration Company, Inc., Los
 Angeles, Calif., a corporation of Delaware

Application November 12, 1940, Serial No. 365,141

4 Claims. (Cl. 255—1.6)

This invention has to do with whipstocks for use in oil well drilling, and comprises as to general form, an elongated body adapted to be carried on the lower portion of a pipe string above a bit or other tool, and used to deflect the tool as drilling proceeds and thereby change the direction of the well bore from the particular course taken above the whipstock.

The customary practice is to lower and set the whipstock in proper position, and to then continue drilling at an angle from the previous course of the well, as determined by the deflection given the bit and drill pipe by the whipstock. The course of the well bore may be so deflected for various reasons, as to reach ultimately a predetermined production zone, or to drill around objects irretrievably lodged in the well. After completion of the whipstock drilling, the pipe string is pulled to remove the whipstock from the well. It frequently happens that the whipstock itself has become so tightly lodged in the well, as by formation imbedding or compacting against the whipstock, as to render the latter removable, if at all, only with difficulty and imposition of excessive strains on the drill pipe, or by the use of special equipment and operations.

My primary object is to provide an improved whipstock construction adapted to facilitate and assure ready removability of the tool regardless of how tightly it may have become lodged in the well by lateral formation pressure or by cavings or by cuttings (all of which are included in the term "formation"). Generally speaking, this object is accomplished by giving the whipstock collapsible characteristics in that it is laterally contractible to produce a substantial reduction in its transverse dimension. Thus, should the tool become so tightly impeded in the formation as to interfere with its removability, it may be laterally contracted to relieve the formation or caving or cuttings pressure against it and permit the tool to be readily withdrawn. Another feature of the invention is the capacity of the whipstock at all times to remain in a normally or laterally expanded condition and to be subject to or capable of lateral contraction only when it becomes lodged in the well.

The various specific forms of whipstocks contemplated by the invention may be described generally as comprising a plurality of longitudinally extending sections capable of relative contractive movement along interengaging inclined or wedge surfaces. As will later appear, the tool may comprise two or more of such relatively movable sections that may be arranged

to give different degrees of radial or circumferential contractibility, according to the particular design preferred. For most purposes, I prefer to construct the tool with one main body section running its full length, and to provide one or more shorter sections movable downwardly relative to the body section and along an inclined surface, or along individual surfaces, to produce lateral contraction of the tool. Normally, the movable section or sections may be releasably held by suitable means such as one or more shear pins. The whipstock is self-collapsible when lodged in the formation, simply by upward pull on the drill string to sever the shear pin and thereby permit the body section of the tool to move upward and away from the then inwardly movable complementary section.

The various features and objects of the invention, together with the details of certain typical and illustrative embodiments, will be understood to better advantage from the detailed description to follow. Reference is had throughout the description to the accompanying drawings in which:

25 Fig. 1 is a view taken in longitudinal section showing one form of the invention;

Fig. 2 is an enlarged cross-section on line 2—2 of Fig. 1;

Fig. 3 is a fragmentary longitudinal section showing a variational form of key interconnecting the relatively movable parts of the whipstock;

Fig. 4 is an enlarged cross-section on line 4—4 of Fig. 3;

Fig. 5 is a side elevation of a variational form 35 of the invention employing a pair of wedge sections similar generally to the single section of Fig. 1;

Fig. 6 is an enlarged cross-section on lines 6—6 of Fig. 5;

Fig. 7 is a side elevation of a further variational form of the invention;

Fig. 8 is an elevation viewing Fig. 7 from the right;

Figs. 9 and 10 are enlarged cross-sections on 45 lines 9—9 and 10—10 of Fig. 7;

Fig. 11 illustrates another variational form having three superposed, relatively movable sections; and

Fig. 12 is a cross-section on line 12—12 of 50 Fig. 11.

It will be understood that aside from the sectional construction of the tool giving it collapsible characteristics, the general form of the tool may be as desired. Typically, I have shown the tool in Fig. 1 to comprise an elongated body,

generally indicated at 10, having a tubular head 11 which shoulders on the conventionally illustrated drill bit 12 to support the whipstock while it is being lowered in the well on the pipe string 13. The whipstock has a main body section 10a which may be formed integrally with the head 11, and which contains a circularly concave recess 14, the base surface 151 (see Fig. 2) of which is inclined as illustrated in Fig. 1, to deflect the bit 12 and pipe string from the well course above the whipstock, after the latter has been set and drilling then proceeds.

The body 10 may be regarded as including a second and relatively movable section 10b that may, and preferably does, extend beyond half the length of the tool from its lower end, in order to render the body laterally contractible throughout the length required to release it from the formation under all ordinary conditions. Body sections 10a and 10b interengage along inclined or wedge surfaces 16 which may exactly or generally parallel the base of recess 14. Section 10b carries a dovetail tongue 16 projecting within an undercut groove or way 17 milled longitudinally in the adjacent face of section 10a, which guide the sections in their relative movement and maintain them at all positions, in engagement along surfaces 15. Body section 10b normally is held in the position of Fig. 1, in which it engages a stop shoulder 18 on section 10a, by means of a shear pin 19, adapted to be severed by upward pull exerted on section 10a, as will presently appear. The sections are retained in engagement permitting relative longitudinal movement, by a suitable key which may consist simply of a strong pin 20 inserted through slots 21 and 22 in section 10b, and threaded at 23 into section 10a. Movement apart of the sections is prevented by engagement of the flanged pin head 20a with surface 24 between slots 21 and 22. As will be apparent, engagement of section 10b with body shoulder 18, and the engagement of key 16 with shoulder 25, relieve pin 19 against strain as a result of downward forces applied through body section 10a. If desired, slot 21 may be closed by a plate 211 to prevent the entry of solids that might interfere with movement of pin 20.

Figs. 3 and 4 illustrate a variational form of key connection between the body sections. Here the key proper comprises a sliding element or plate 26 placed within a recess 27 in body section 10a, and having integrally formed or attached thereto as by welding, a pin 28. In assembling the key structure within the body sections, plate 26 is put into recess 27 and a plate 29 containing a slot 30 through which pin 28 passes, is placed over the key 26 and welded within recess 27. Section 10b is then applied in the position of Fig. 1 by placing opening 31 over the pin 28 and welding the section to the pin as at 32. A suitable lubricant may be introduced to slot 30 and the unoccupied portion of slot 27, through passages 33 and 34 in the pin 28, as best shown in Fig. 4. As will be understood, the sections 10a and 10b normally will be held against relative movement by a shear pin as at 19 in Fig. 1.

The tool normally will be used in the condition shown in Fig. 1, and in fact it will remain in that condition during all operations unless it becomes lodged in the well so as to require collapsing to facilitate its removal. While being lowered and set within the well, the whipstock may be held against rotation relative to the pipe string, by any suitable means such as a spot weld at W or a shear pin S, either of which may be

broken or sheared after the tool is set and drilling is to proceed, by lowering the pipe string. Assuming that after whipstock drilling the tool has become imbedded in formation exerting such lateral pressure against the body 10 as to prevent or seriously interfere with its withdrawal, the tool may readily be freed simply by exerting sufficient pull on the pipe string to shear pin 19 and permit upward movement of the main body section 10a relative to section 10b. Due to the angularity of the interengaging surfaces 15 of the members, upward movement of section 10a in effect reduces the transverse dimension of the body assembly, permitting it to move away from or reduce its pressure against the formation, to the point that the tool can be withdrawn without difficulty. Section 10b is of course prevented from moving upwardly, due to its weight and its engagement with the formation. When key pin 20 reaches the upper end of slot 22, or in the form of Fig. 3, when the bottom shoulder 27a of slot 27 engages the lower end of key 26, section 10b of the body then is carried upwardly and withdrawn together with the main body section. Finally it may be observed in connection with the described form of the invention, that the interengaging surfaces 15 may have any desired angularity depending upon the extent to which the tool is to be laterally contractible.

The form of the invention shown in Fig. 5 is generally similar to the described embodiment except that it is rendered contractible to a greater degree circumferentially of the tool, by providing a plurality of wedge sections applied to as many wedge surfaces opposite the recess 14. While any suitable number may be used, I have shown typically two wedge sections 10c and 10b, applied to vertically inclined surfaces 36 and 37 on the body section 38, see Fig. 6, sections 10c and 10b being held against movement by shear pins 39 and having key pin connections 40 with section 38 as in Fig. 1. As will be observed from Fig. 6, sections 10c and 10b may together extend in excess of 180° about the body, with the advantageous result that the tool thereby becomes laterally or radially contractible over a corresponding portion of its circumference. This permits release of the tool regardless of the circumferential distribution of lateral formation pressures, since the tool is laterally contractible across all diameters.

The form of the invention illustrated in Figs. 7 to 10 differs from those previously described in that instead of the wedge sections being applied to a surface of the main body section opposite its longitudinal recess, the body of the tool is, in effect, split longitudinally along an inclined surface generally normal to the guide recess, and is made in sections movable relatively along such inclined surface. Viewing the tool in the aspect of Fig. 8 (looking into the guide recess 42) the body 43 is divided along angular or wedge surfaces 44, into a main section 43a and a wedge section 43b attached to the former section by shear pin 45. Section 43b carries a spline 46 projecting within groove 47 in section 43a, and as in Figs. 1 and 5, limited relative movement of section 43a upwardly relative to section 43b after shearing of pin 45 is permitted by pin 48 extending through a slot 49 in section 43b and threaded at 50 into the main body section.

The final form of the invention shown in Figs. 11 and 12 is characterized by the provision of a plurality in excess of two, of relatively longitudinally movable sections that may be employed to give the tool a greater degree of transverse

contractibility by reason of the multiplicity of wedge engaging sections. Any suitable number of such sections may be used in this construction, three being shown as typical. Applied directly to the main body section 51 and in engagement therewith along inclined surface 52, is an intermediate section 53 releasably held in its normal position by shear pin 54. A spline 55 on section 53 projects within way 56 in the main section 51, and the two sections are held together permitting their relative movement, by pins 57 threaded into section 51 through slots 58 and 59. A third wedge section 60 engaging the outside of section 53 along inclined surfaces 61 paralleling surfaces 52, has a spline 63 working within way 64, and is releasably attached to section 53 by shear pin 65. Sections 53 and 60 are held together to permit their relative movement, by pin 66 inserted through slots 67 and 68.

Upward pull on the main body section 51 when the tool becomes lodged, may shear either or both of pins 54 and 66, permitting relative movement of any two or all three of the body sections, as the case may be. The tendency for both pins 65 and 54 to shear will of course increase according to the tightness with which the body is lodged in the well. And accordingly, the greater will be the capacity of the tool for freeing itself from the formation by reason of the increased contractibility permitted by relative movement of all three sections.

I claim:

1. A retrievable well whipstock comprising a body having a pair of sections that are relatively movable to transversely contract the body and thereby facilitate its removal from the well, and means connecting said sections to maintain the body in transversely expanded condition while it is being lowered in the well, said connecting means thereafter being releasable to permit said body contracting relative movement of the sections.

2. A retrievable whipstock comprising a trans-

versely contractible body adapted to be lowered and set in a well in transversely expanded condition, said body including a pair of vertically elongated oppositely disposed wedge sections that are relatively vertically movable by an upward pull on one section, when the body becomes lodged in the formation, to contract the body transversely and thereby facilitate its removal from the well, and a connection between said sections holding them against body contracting relative movement while the body is being lowered in the well, said connection being adapted to be released by stresses tending to move one section vertically relative to the other section.

- 15 3. A retrievable whipstock for use in a well, comprising a body section and a vertically elongated wedge section engaging the body along an inclined surface, means for connecting said body section to a pipe string, and a shear pin normally holding said sections against relative vertical movement to maintain the whipstock in transversely expanded condition, said pin being shearable by stresses tending to move the body section vertically relatively to the wedge section.
- 20 4. A whipstock comprising a portion having a tool-guiding face, a portion backing said tool-guiding portion and forming therewith an enlargement of the lower part of the whipstock, and means for securing said portions together to provide such enlargement of the lower part of the whipstock, the enlargement of the lower part of the whipstock in comparison with the upper part thereof being primarily due to said backing portion so that when the tool-guiding portion is free to move upwardly relatively to the backing portion the former may be readily withdrawn from a hole, said securing means releasing said portions for said movement of the tool-guiding portion upwardly relatively to the backing portion under stresses tending to prevent removal of the whipstock from the hole.

JOHN E. BRANTLY.
